[57] **CLAIM**

The ornamental design for an enclosure for a mobile microphone-transmitter assembly, substantially as shown and described.

DESCRIPTION

FIG. 1 is a front perspective view of an enclosure for a mobile microphone-transmitter assembly showing the new design;

FIG. 2 is a rear perspective view of the enclosure shown in FIG. 1;

FIG. 3 is a front view of the enclosure shown in FIG. 1; FIG. 4 is a rear view of the enclosure shown in FIG. 1; FIG. 5 is a right side view of the enclosure shown in FIG. 1;

FIG. 6 is a left side view of the enclosure shown in FIG. 1;

FIG. 7 is a bottom plan view of the enclosure shown in FIG. 1; and

FIG. 8 is a front perspective view thereof; the broken lines representing a human form is shown for illustrative purposes only.

FIG. 1

FIG. 2

FIG. 4

FIG. 3

FIG. 5

FIG. 6

FIG. 7

FIG. 8
